SIDE WALL SAMPLER

Paul Dean Cornelius, Hollydale, Calif., assignor to
 Byron Jackson Co., Vernon, Calif., a corpora-
 tion of Delaware

Application March 7, 1949, Serial No. 80,058

36 Claims. (Cl. 255—1.4)

1

This invention relates generally to well drilling apparatus and is particularly directed to improvements in coring or sampling devices for taking a formation sample from the side wall of a well bore.

In recent years there has been a trend in the art of drilling oil and gas wells toward completion of the drilling from the surface to the total depth without interruption, thereby avoiding expensive standby time previously required while cores or formation samples were obtained. After such drilling operation is completed and while the well bore yet contains drilling fluid, the entire length of the uncased bore is electrically logged in order to select the most promising strata for production of oil or gas. From the information produced by the electrical logging devices the operator may then utilize a side wall sampler for obtaining cores from the side walls of the bore hole in the regions of the potentially productive formation. While this practice of drilling to the full depth before taking cores is efficient in that it involves a minimum amount of time at the least expense, it does require that a reliable sampling tool be available for extracting formation samples from the side wall of the well bore, which samples will be suitable for complete geological analysis. It is the primary object of the present invention to provide such a side wall sampling tool of novel and improved construction.

Side wall sampling devices heretofore used in field conditions are of three types:

(1) Punch types. These usually employ a core-receiving tube having one end pivotally secured to the lower end of a drill string and arranged to be projected without rotation into the side wall so as to punch or tear out a fragment thereof upon vertical movement of the drill string. A serious disadvantage of the punch type sampler is that it is limited to use with well formations which are comparatively soft. Another difficulty is that the samples obtained are usually so crushed and broken that a full geological analysis is difficult to obtain. Another disadvantage with the punch core sampler is that the sample it obtains lies immediately adjacent the bore of the hole and not remote therefrom so that the sample may be contaminated by the action of the drilling fluid.

(2) Hollow bullet types. Devices of this type fire one or more hollow bullets which may be retrieved after they have been fired into the side wall at the desired level. This type of sampler apparatus is subject to the same disadvantages as the punch type. Furthermore, it yields a sample of even smaller size.

2

(3) Rotary types. These have commonly employed a rotary core bit and sample-receiving tube which are rotated by the drill string. Ordinarily a nonrotary housing is releasably anchored within the well bore at the lower end of the drill string and serves as a guide for the rotary core bit. This type of sampler yields the best core for geological analysis and it is capable of operation in hard formations. A disadvantage of this type of sampler as heretofore employed is that the drill string must necessarily be rotated at a relatively slow rate in order to avoid excessive movement of the nonrotary housing at the lower end of the drill string. Considerable time is thus required to cut a sample from the side wall of the bore hole. Since the sample undergoing extraction is exposed to the drilling fluid it is subject to considerable contamination. Furthermore, side wall samplers of the rotary type have heretofore been constructed so that an accidental increase in pressure of the wall fluid might result in sticking of the sample-taking tube in the formation. In such devices the tube sometimes becomes so tightly wedged in the formation that it cannot be removed by a wire line or by the drill pipe. Thus an expensive fishing job may be required. Other types of rotary side wall samplers have been proposed and among these is a type embodying a rotary sampling tool driven by a prime mover positioned in the well as distinguished from rotation by the drill pipe. However, in this proposed construction the sampling tool is not retrievable while leaving the prime mover in the hole, and hence the drill string must be withdrawn and reinserted section by section for each sample obtained. The limitations and disadvantages enumerated above are avoided by devices employing my present invention, which devices are capable of extracting relatively long samples suitable for complete geological analysis from hard or soft strata on the side wall of the well bore in a minimum amount of time. Accordingly, one of the principal objects of this invention is to provide a novel side wall sampling tool for wells capable of extracting from formations a core in its natural undisturbed condition and of sufficient size for geological examination. A related object is to provide a novel tool of this type capable of extracting a formation sample which is laterally displaced a sufficient distance from the side wall of the well bore so as to be substantially uncontaminated by the drilling fluid contained within such well bore.

More particularly it is an object of this invention to provide side wall sampling apparatus retrievable on a wire line through the interior of

the drill pipe and having a coring tool adapted to be rotated by power means at the lower end of the drill string.

Another object is to provide drilling apparatus for use in a bore hole and having a prime mover mounted in a housing carried on the pipe string, the prime mover being adapted to rotate a cutting tool retrievable through the drill string.

Another object is to provide improved means for advancing and retracting the coring tool and sample-receiving tube.

Another object is to provide a novel form of signal means for indicating when the coring device has been advanced and fully retracted into the retrievable assembly.

Another object is to provide a novel form of sample tube which is particularly well adapted to transmit both torsion and axial forces to the coring bit.

Another object is to provide a side wall sampling device having a sealed mechanism actuated by pressure of drilling fluid, yet sealed from contact therewith.

A further object is to provide a valve device at the lower end of the sampling apparatus which functions to maintain a back pressure of well fluid on the mechanism in order that the advancing and retracting means for the coring tool may function without danger of sticking while in its extended position.

Other and more detailed objects and advantages will appear hereinafter.

In the drawings:

Figure 1 is a longitudinal sectional view partly broken away showing a preferred embodiment of my invention, the central retrievable portion thereof being shown in elevation. This figure is separated into three portions in order that the entire length may be shown in convenient size. It will be understood that Figure 1b shows that portion of the device between the lower end of Figure 1a and the upper end of Figure 1c.

Figure 2 is a sectional view similar to Figure 1c showing the positioner device and the rotary coring tool in extended position.

Figure 3 is a longitudinal sectional elevation partly broken away and showing details of construction of the inner retrievable assembly. This figure is separated into three parts, 3a, 3b and 3c in the manner similar to that described in connection with Figure 1.

Figure 4 is an enlarged sectional elevation of a portion of the retrievable assembly shown in Figure 3b with internal parts moved to a different position.

Figure 5 is a sectional view similar to Figure 4 but with the internal parts moved to a different position.

Figure 6 is a sectional view similar to Figures 3a and 3b showing the internal parts in position for signaling that the coring tool has completed its cycle and is in retracted position.

Figure 7 is an exploded view of certain of the parts illustrated in Figure 3b.

Figure 8 is a longitudinal sectional view showing the core bit, core tube and sample tube assembly.

Figure 9 is a transverse sectional view taken substantially on the lines 9-9 as shown in Figure 8.

Figure 10 is a transverse sectional view taken substantially on the lines 10-10 as shown in Figure 2.

Figure 11 is a transverse sectional view taken 75

substantially on the lines 11-11 as shown in Figure 3a.

Figure 12 is a transverse sectional view taken substantially on the lines 12-12 as shown in Figure 3b.

Figure 13 is a longitudinal sectional view showing a modification.

Figure 14 is a perspective view showing a crank and the use thereof in setting the internal mechanism of the retrievable assembly prior to use.

Referring to the drawings, the sectional string of pipe 10 extends into a well bore 11 and is connected to a sub 12 at its lower end. The sub in turn is attached to the upper end of a body 15 or housing 13 which encloses the side wall sampling device. The housing 13 may be composed of several sections 14, 15, 16, 17 and 18 threaded together end to end. A portion of the housing encloses a turbine unit generally designated 19. 20 This turbine unit is driven by a flow of mud fluid and acts to rotate a retrievable core barrel assembly 20. The lower end of the assembly 20 is provided with a core bit 21 which may be hydraulically projected laterally through a side window 22 in a housing section and into the formation adjacent the well bore. A core cut from the formation is then retracted with the bit 21 back into the interior of the housing. The assembly 20 including the core bit 21 and core may then be retracted as a unit on a wire line upwardly through the bore 23 of the pipe string 10. The core is extracted and the assembly 20 may be lowered into the hole on a wire line and additional cores taken without requiring that the housing 13 be removed from the well hole.

Referring more particularly to the detailed construction of a preferred embodiment of my invention, the retrievable assembly 20 is adapted to be received within the housing 13. A shoulder 7 on the assembly rests on an annular abutment 8 provided on the rotary sleeve 9. The sleeve 9 is carried on the thrust bearing 24 and constitutes the rotor of the turbine generally designated 19. This turbine 19 includes a plurality of stator rings 26 and a plurality of rotor rings 27 arranged in alternate relationship. The blades 28 on the stator rings 26 are curved in one direction and the blades 29 on the rotor rings 27 are curved in the other direction, as clearly shown in Figure 1b. Each of the stator rings is provided with a lower internal thread 30 adapted to engage an upper external thread 31 on the adjacent stator ring. The support ring 32 for the bearing 24 is threaded to the lowermost stator ring 26 and rests on the shoulder 33 provided at the upper end of the housing section 16. A collar 34 rests on the uppermost stator ring 26 and confines the outer rim of a screen 35 against a shoulder 36 on the lower end of the housing section 14. From this description it will be understood that the housing section 15 encloses the turbine 19 and confines the stator rings 26 between shoulders on the housing sections 14 and 16.

Means are provided for moving the housing 13 away from a central position within the well bore 11 and for crowding it against the side wall of the well bore. As shown in the drawings, this means includes the housing section 18 which comprises a cage for the positioner unit generally designated 37. A sliding head 38 is provided with a piston 39 at its upper end and a flange 40 at its lower end which are adapted to slide within the central axial bore 41. One or more seal rings 42 may be provided on the piston 39. A wedge cam 43 is pivotally secured to the cage

18 by means of the pivot bolt 44. The wedge cam 43 is also pivotally connected to a cross-head member 45 having cylindrical ends 46 adapted to roll on parallel horizontal guides 47 provided on the sliding head 38. The arrangement of parts is such that downward movement of the head 38 within the cage 18 acts to move the cam member from the retracted position shown in Figure 1c to the extended position shown in Figure 2. In the latter position the operative surface 48 on the cam member engages the side wall of the well bore 11 on one side, thereby displacing the cage 18 into contact with the side wall on the other side of the bore hole 11. In the latter position the side opening window 22 15 in the housing section 17 lies adjacent the side wall of the bore hole.

Downward motion of the sliding head 38 is resisted by means of the coil spring 49 positioned at the lower end of the bore 41. The spring 49 is positioned on a support collar 50 held in place by means of a retaining ring 51. The lower end of the cage 18 is attached to a hollow plug 52. A replaceable bushing 53 is mounted in the piston 39 and provided with a central opening 52. The opening 52 is closed by a flapper valve 54 pivotally supported at 55 and maintained in closed position by means of a relatively weak coil spring 56. When a supply of fluid under pressure is delivered to the space 57 above the piston 39, the flapper valve 54 immediately opens and allows fluid to pass through the opening 52 and downwardly into the interior of the head 38. The fluid passes outwardly through the window 58 through which the cam member 43 operates and also passes downwardly through the openings 59 and 60 into the bore hole 11. The opening 52 is proportioned to allow a relatively small rate of flow of well fluid without offering back pressure sufficient to depress the piston 39. When the rate of flow of well fluid is sufficiently high to actuate the turbine 19, the back passage caused by the restricted orifice 52 is sufficient to depress the sliding head 38 and extend the cam member 43 through the window 58. The function of the flapper valve 54 is to prevent detritus in the well hole from passing upwardly into the interior of the upper housing sections when the housing 13 is initially lowered into the hole on the end of the pipe string 10.

In order to prevent excessive back pressure in the space 57 and thereabove, a relief valve assembly is provided on the piston 39. As shown in the drawings, this valve assembly includes a replaceable seat 61 cooperating with a valve head 62 which is guided for movement by means of lateral fins 63. The valve head is carried on a valve stem 64 slidably mounted for movement within a guide 65 provided on the head 38. A coil spring 66 acts resiliently to maintain the valve head 62 in sealing relationship with respect to the valve seat 61. When the pressure differential across the piston 39 exceeds a predetermined value the valve head 62 moves downwardly to permit fluid to flow through the central opening in the seat 61.

Referring particularly to the construction of the retractable assembly 20, the pulling plug 70 is provided with a shoulder 71 for engagement by a conventional overshot (not shown). This plug is attached to the upper end of the signal body 72 by means of threads 73 and pins 74. The lower end of the signal body 72 is connected by threads 75 to the upper end of the cylindrical pipe 76. An annular piston 77 is slidably mounted within

the cylindrical bore 78 of the pipe 76 and is provided with one or more sealing rings 79 and 80. A tube 81 extends centrally through the piston and is sealed therewith by means of the inner seal ring 80. The annular piston 77 moves downwardly with respect to the stationary pipe 76 and tube 81 when mud fluid under pressure enters the lateral port 95 in the pipe 76 and passes into the space 82 above the annular piston 77. The piston 77 is thus free-floating and its function is to separate mud fluid in the chamber 82 from oil contained in the chamber 83 below the piston 77. The tube 81 is threadedly connected at its upper end to the signal rod 84 which is slidably mounted within the signal body 72. The rod 84 and its mounting are more fully described hereinafter.

The lower end of the pipe 76 is connected by threads 85 to the driving body section 86. Pivot dogs 87 are mounted in recesses 88 on the body 86, and compression springs 89 are provided to move the dogs in a direction to project the driving edges 90 thereof outwardly beyond the periphery of the body 86. These dogs are adapted to engage within notches 91 formed on the turbine rotor 9 to provide a driving engagement for rotating the retrievable assembly 20. The lower end of the body 86 is connected by threads 92 to the shell 93 which encloses the relatively long coil spring 94.

The lower end of the tube 81 is connected by thread 96 to the upper end of the slotted member 97. As clearly shown in Figure 7 this member is provided with a flange 98 and a downwardly extending cylindrical part 99 having a transverse slot 100 formed therein. The slot 100 receives a pair of upwardly extending lugs 101 carried on the collar 102. A cylindrical skirt 103 encircles the member 97 below the level of the flange 98 and is attached to the slotted member 97 by means of screw fittings 104. This skirt 103 is provided with a pair of bayonet slots 105, each having an upper vertical portion 106, a central horizontal portion 107, and a lower downwardly extending vertical portion 108. Radially extending pins 109 are threadedly secured to circulation tube 110 which extends through the collar 102 and slotted member 97. The pins 109 extend radially through openings provided in the collar 102 and project into the bayonet slots 105.

The circulation tube 110 extends downwardly through the shell 93 and carries an abutment piece 111 near its lower end. A forward piston 112 is supported on the upper end of the spring 94 and is slidably mounted within the cylindrical bore 113 of the shell 93. A bushing 114 fixed on the piston slidably receives the outer surface of the lower portion of the circulation tube 110. The feed piston 112 is caused to move downwardly under hydraulic pressure delivered to the space 115 in a manner described below. The piston moves downwardly within the bore 113, compressing the spring 94, and eventually contacts the abutment piece 111. This pulls the circulation tube 110 downwardly and therefore moves the pins 109 downwardly within the upper portions 106 of the bayonet slot 105. A torsion spring 116 having its lower end secured to the skirt 103 at 117 has its upper end secured to the collar 102 at 118. A distance piece in the form of a sleeve 116a is positioned within the spring 116. Accordingly, when the radial pins 109 enter one end of the horizontal portion 107 of the bayonet slot 105, the torsion spring 116 turns the collar 102 through approximately 90° and brings the lugs 101 out of registry with the slot 100.

75

Continued downward movement of the feed piston 112 causes the circulation tube 110 to move downwardly with it, and this action brings the radially extending pins 109 down into the vertical portions 108 of the bayonet slot 105.

This continued downward movement of the circulation tube 110 brings the lower tapered end 119 of the large trigger collar 120 into contact with the inner portion of the latching lug 121. The collar 120 is attached to the circulation tube 110 by means of the pin 122. The latching lug 121 is pivotally mounted on a vertical pin 123 fixed on the upper end of the valve body 124, and it operates in a horizontal slot 125 formed in the valve body. As shown in Figures 4 and 12, when the lower tapered end 119 on the trigger collar 122 engages one end of the latching lug 121, it moves the other end radially inwardly so that said other end no longer overlies the shoulder 126 formed near the upper end of the valve housing 127. The latching lug 121 is arcuate in shape so that in its inoperative position it lies completely within the annulus formed between the bore 128 of the valve housing 127 and the external cylindrical surface of the valve body 124. When the arcuate latching lug 121 is in this inoperative position as shown by the dotted lines in Figure 12, the valve body 124 is released for movement with respect to the valve housing 127.

The valve body 124, valve housing 127, and associated parts comprise a four-way valve assembly generally designated 129. The function of this four-way valve assembly is to admit pressure fluid above the feed piston to move it downwardly while exhausting fluid below the piston, and then when the feed piston has reached the lower end of its stroke to reverse the action so that the pressure fluid is applied beneath the piston and exhausted above it. As shown in the drawings, Figure 4 shows the passageways of the valve assembly 129 arranged to cause downward movement of the feed piston 112. Oil under pressure from the chamber 83 below the barrier piston 77 passes downwardly through the interior of the body section and into the passageway 130 formed in the upper end of the valve body 124. This passageway communicates by way of port 131 with an annular groove 132 provided in the valve housing 127. This annular groove 132 is also in communication with passageway 133 formed in the valve housing 127 and communicates with the space 115 above the feed piston 112. The space 134 below the feed piston 112 communicates by way of lateral port 135 and longitudinal passage 136 formed in the wall of the shell 93 with the circumferential groove 137 formed in the valve housing 127 between the sealing rings 138. This annular groove is connected by lateral port 139 to annular groove 140 formed in the outer surface of the valve body 124. A port 141 connects this groove 140 to the annular space 142 between the circulation tube 110 and the valve body 124. A port 143 is provided through the wall of the circulation tube 110 so that pressure fluid exhausting from the space 134 below the feed piston 112 passes downwardly through the interior of the tube 110.

Figure 5 shows the position of the passageway in the four-way valve assembly 129 corresponding to delivery of pressure fluid to the space 134 below the feed piston 112 and exhaust of pressure fluid from the space 115 above the feed piston 112. The valve body 124 is latched with respect to the valve housing 127 while the valve parts are in position to cause the feed piston

112 to move downwardly, but at the lower end of its stroke the circulation tube 110 is moved axially to trip the latching lug 121 and to release the valve body 124 for axial movement with respect to the valve housing 127. The valve body 124 moves downwardly against the action of the compression springs 144 because of the higher fluid pressure which exists within the space 145 as compared to the relatively low back pressure in the interior of the circulation tube 110 and hence in space 146. The spring 144 rests on a closure plug 148 threaded to the lower end of the valve housing 127. Upon release of the arcuate latch 121 the valve body 124 moves with a snap action from the position shown in Figure 4 to the position shown in Figure 5. In the latter position passageway 133 connects the space 115 for exhaust through the interior of the circulation tube 110 by way of port 141, annular space 142, and port 143 in the wall of the circulation tube 110. At the same time, pressure fluid is admitted from the space 145 above the four-way valve assembly 129 into the passageway 130 and ports 147 and 139. The pressure fluid then passes into ring groove 137 and into the passageway 136 formed in the wall of the shell 93. The pressure fluid emerges through port 135 into the space 134 below the piston 112.

The passageway 136 may be formed in the wall of the shell 93 in any convenient manner. I prefer to form a long V-shaped slot extending inwardly from the outer periphery of the shell 93 and then to weld a cover strip over the outer portion of the slot to form the passageway 136.

When the feed piston approaches the upper end of its stroke it engages the stop element 149 which is fixed on the circulation tube 110 and positioned within the space 115. This stop element may comprise a pair of half rings mounted in a circular recess 150 on the tube 110 and held in place by means of a retaining ring 151. Continued upward movement of the feed piston 112 carries the stop element 149 and circulation tube 110 upwardly therewith. Upward motion of the feed piston continues until the upper surface of the stop element 149 engages the lower side 152 of the closure collar 148. The fluid pressure which acts to move the feed piston downwardly applies an equal force tending to raise the retrievable assembly 20 upwardly away from the supporting shoulder 8. However, this force is overbalanced by the weight of the assembly plus the relatively large downward force applied to the assembly by the pressure of the mud fluid within the interior of the drill string 10. The result is that the sleeve 9 of the retrievable assembly 20 remains in position while the core bit 21 is advanced to the formation.

Rotary motion transmitted from the turbine rotor 9 to the driving body 86 through the pivoted lugs 87 reaches the feed piston 112 through the sleeve 93 and the long coil spring 94. The coil spring 94 therefore provides a resilient drive for rotating the feed piston and its associated parts as well as for assisting in returning the feed piston 12 to its upper position. A hollow piston rod 153 extends downwardly from the feed piston and through the interior of the coil spring 94. The hollow piston rod 153 is slidably received in bore 154 in the closure 155 attached to the lower end of the shell 93. A seal ring 156 prevents leakage between the closure and hollow piston rod. The projecting end 157 of the hollow piston rod 153 is threaded to a driving collar 158. The driving collar 158 is threadedly

connected at 159 to the core-taking unit generally designated 160. This unit 160 includes a pair of mounting members 161 secured to the opposite ends of a metallic coil spring 162. The upper member 161 is threadedly engaged with the driving collar 158. The spring 162 is imbedded in a cylindrical sheath of rubber 164 to form an integral resilient tube 163.

An annular core-cutting bit 21 of any preferred design is threaded to the member 163 at 165. This annular core-cutting bit may be provided with the usual formation-engaging teeth 166. Any preferred form of core catcher assembly 167 may be provided. As shown in the drawings this core catcher assembly includes a ring 168 having a plurality of fingers 169 pivotally attached thereto at 170. It is the function of the fingers 169 to prevent a core from moving out of the interior of the core-taking assembly 160 once it has entered.

A core-receiving tube 171 is fastened on a collar 172 which is in turn secured on the ring 173. The latter ring is fixed with respect to the ring 168. The tube 171 is composed of interlocking spiral pieces which form a flexible and fluid-tight receiver for the core. The upper end of the flexible tube 171 carries a valve body 174 having a ball 175 adapted to rest on a seat 176. The ball 175 acts as a check-valve to prevent pressure from being applied to the upper end of the core-receiving flexible tube 171. Any fluid pressure in this region would act to impede the entrance of the core into the tube 171.

The driving collar 158 is slidably received within the bore 177 of the tail pipe 178 which extends from the curved footpiece 179 to the supporting assembly 32 for the thrust bearing 24. The curved passage 180 in the footpiece 179 communicates with the side opening window 22 described above. An insert member 181 may be mounted in the lower end of the curved passage and provided with an inner rubber sleeve 182 to resist wear. As the rotating hollow piston rod 153 moves downwardly within the tail pipe 178 it causes the resilient tube 163 to rotate and to move outwardly through the window 22. The coring head 21 drills into the formation, leaving a stationary central axial core projecting into the flexible core-receiving tube 171. The driving tube 163 must be sufficiently flexible to rotate within the curved footpiece 179, must carry adequate torque for turning the bit 21, and must carry axial load for forcing the bit 21 into the formation. I have found that the tube 163 composed of a metallic coil spring imbedded within a cylindrical rubber sheath performs these various functions in a highly satisfactory manner. The service on this part is severe, and it is absolutely essential that no fractures or failures occur. The particular construction illustrated has been found to give excellent results in actual tests. At the end of a long period of service the rubber-metal bond may be broken or the rubber itself may rupture; at such time the old rubber may be burned off and new rubber may be molded about the spring.

Mud fluid is supplied to the cutting bit 21 as is customary in rotary well drilling practice. This mud fluid enters the screen 183 provided on the signal body 72 and passes inwardly through ports 184 and 185. The mud fluid then passes through the restriction bean 186 and enters the upper end of the tube 81. The lower end of this tube is in communication with the upper end of the circulation tube 119 and hence

mud fluid passes downwardly through the fitting 187 at the lower end of the tube 110. The mud fluid then passes through the hollow piston rod 153 and into the interior of the flexible driving tube 163. The check valve 175 prevents entrance of mud fluid into the interior of the core-receiving flexible tube 171. The mud fluid therefore passes through the annular space 188 between the tubes 171 and 163 and through passageways 189 formed in the coring head 21 and reaches the teeth 166 through openings 190. As the core enters the core-receiving tube 171, pressure is not developed within the upper end of the tube 171 because the check valve allows any fluid therein to escape.

When the feed piston has moved to the lower end of its travel and then has fully retracted as explained above, the flexible driving tube 163 and coring head 21 are withdrawn back into the interior of the housing 13. Means are provided for signaling to the operator at the ground surface when this cycle has been completed. As shown in the drawings, this means includes a restriction valve generally designated 191. This valve acts to restrict the flow of mud fluid entering the device from the sub 12 when the core-taking cycle has been completed. The restriction in the circulation path is reflected by an increase in pressure at the surface, and this is indicated on a pressure gage (not shown).

When the pressure suddenly increases the operator is informed that the core-taking cycle has been completed. An overshot (not shown) is then lowered into the well pipe 10 on a wire line to engage the pull plug 70 and the entire retrievable assembly 20 is withdrawn as a unit.

The signal operating means shown in the drawings includes the latching parts 192 and 193 which are substantially duplicates. As shown in Figures 3a, 6 and 11, each of these parts is substantially U-shaped with one leg of each engaging within the opening of the other. Coil springs 194 are confined within the parts 192 and 193 and act resiliently to maintain them in retracted position. The latching parts are arranged to operate in a cross-slot 195 provided in the signal body 72 and are arranged to underlie an internal shoulder 196 formed on the signal valve 197. When the latching parts are retracted as shown in Figure 6 so that they no longer underlie the shoulder 196, the signal valve 197 drops by gravity and by the velocity effect of the mud fluid stream passing through the restricted opening 198 formed in the insert piece 199. A coil spring 200 may be used if desired to supplement the action of gravity and of the mud fluid stream to move the signal valve from the inoperative position shown in Figure 3a to the operative position shown in Figure 6. A bulbous rubber sleeve 201 may be fixed on the valve 197, and this sleeve closely approaches the diameter of the opening 198 but does not completely fill it so that when the signal valve 197 is in the position shown in Figure 6 the flow of mud fluid is restricted but not entirely shut off.

Means are provided for retracting the latching members 192 and 193, and as shown in the drawings this means includes a pointed pin 202 fixed on the upper end of the signal rod 84. The signal rod is slidably mounted within the signal body 72 and is provided with a vertical slot 203 for reception of a pin 204 fixed on the body 72. The slot and pin cooperate to prevent relative rotary movement between the rod 84 and body 72. Since the rod 84 is carried on the upper end

11

of the tube 81 it moves as a unit therewith. Upward movement of the rod 81 and hence of the rod 84 and latch actuating pin 202 is caused by upward movement of the circulation tube 110 when the feed piston 112 returns to the upper end of its stroke. The downward movement of the feed piston resulted in movement of the lugs 101 out of the slot 100 as described above and repositioning of the lugs 101 in a position out of registry with the slot 100. Accordingly, when the circulation tube 110 is moved upwardly as the feed piston completes its operative cycle, the upper faces 205 of the lugs 101 engage the lower surfaces 206 on the cylindrical extension 99 of the member 97. Continued upward movement of the feed piston 112, circulation tube 110 and lugs 101 serves to raise the member 97 and tube 81. This in turn moves the signal rod 84 upwardly to cause the latch operating pin 202 to retract the latch members 192 and 193. The signal valve 197 then moves downwardly as described above to restrict the flow of mud fluid and thereby apprise the operator that the retractable unit 20 is ready for removal through the pipe string 10.

When the retractable unit 20 reaches the surface the core-taking unit 160 is removed from the driving collar 158 by disengaging the threads 159. The core is then removed from the tube 171 for geological analysis. The plug 201 in the side of the body 86 is removed to permit introduction of a new supply of oil or other hydraulic fluid into the space 83 below the barrier piston 87. A suitable tool such as, for example, the crank tool 208 as shown in Figure 14, is inserted through the open lower end of the hollow piston rod 153. A laterally projecting part 209 on the end of the tool 208 is inserted into the bayonet slot 210 in the fitting 187 on the lower end of the circulation tube 110. The crank is turned to oppose the action of the torsion spring 116 and a thrust is applied to move the laterally extending pins 109 into the upper vertical portions 106 of the bayonet slots 105. This action resets the tool for use and in effect contracts the overall length of the tubes 110 and 81. A coil spring 211 returns the valve latch 121 to its operative position. The signal valve 197 is raised against the action of the coil spring 200 to permit the latching members 192 and 193 to move outwardly into the operative position. A new core-taking assembly 160 is threaded to the driving collar 158 and the tool is ready for lowering again into the pipe string 10 on a wire line.

When the supply of mud fluid is cut off at the surface the positioner unit generally designated 37 moves back to its inoperative position as shown in Figure 1c. The pipe string may then be manipulated to present a new location for taking another core. This process may be repeated and as many side wall sample cores taken as desired without requiring that the pipe string 10 be removed from the well bore 11.

My invention is not limited to devices for taking a core from formation adjacent a well bore, but may also be employed in connection with the drilling of lateral drainage holes in "tight" formations, and may also be used for drilling holes in casing. When a hole is to be drilled in the casing the surface 48 on the wedge cam 43 is curved to fit the inner surface of the casing wall and may be serrated to prevent slipping. It will be understood that in this specification and claims the words "bore hole" include either a cased or an uncased hole. In this connection the

12

devices may be used as a coring tool for taking a formation sample through the wall of the casing. In such cases the rotary bit first cuts a hole in the wall of the casing and is subsequently extended through the hole to take a core from the well formation. In the modified form of my invention illustrated in Figure 13, the barrier piston 77 is not used. Instead mud fluid enters through the port 95a and passes through the annular passage 220 into the space 221. Mud fluid also passes inwardly through the screen 183a and into the interior of the signal rod 84a through lateral ports 184a and 185a in the manner described above. The remainder of the device in this modified form is substantially the same as that previously described, and the similar parts are designated by the same numeral with the suffix *a*.

Having fully described my invention, it is to be understood that I do not wish to be limited to the details herein set forth, but my invention is of the full scope of the appended claims.

I claim:

1. Drilling apparatus for use in a bore hole, comprising in combination: a housing adapted to be secured to a pipe string and positioned within the bore hole, a prime mover in the housing having a rotary drive element, and a retrievable drilling unit including a rotary cutting tool adapted to be lowered through the interior of the pipe string into driving relationship with said drive element.

2. Drilling apparatus for use in a bore hole, comprising in combination: a housing adapted to be secured to a pipe string and positioned within the bore hole, a prime mover in the housing having a rotary drive element, a retrievable drilling unit including a rotary cutting tool adapted to be lowered through the interior of the pipe string into the housing, the drive element and the drilling unit having cooperating parts providing a releasable driving connection whereby the retrievable drilling unit and cutting tool may be rotated by the rotary drive element.

3. Drilling apparatus for use in a bore hole, comprising in combination: a housing adapted to be secured to a pipe string and positioned within the bore hole, a prime mover in the housing driven by pressure fluid supplied through said pipe string, said prime mover having a rotary drive element, a retrievable drilling unit including a rotary cutting tool adapted to be lowered through the interior of the pipe string into the housing, and cooperating parts on the drive element and the drilling unit providing a releasable driving connection whereby the retrievable drilling unit and cutting tool may be rotated by the rotary drive element.

4. Drilling apparatus for use in a bore hole, comprising in combination: a housing adapted to be secured to a pipe string and positioned within the bore hole, a prime mover in the housing driven by pressure fluid supplied through said pipe string, said prime mover having a rotary drive element, a retrievable drilling unit including a rotary cutting tool adapted to be lowered through the interior of the pipe string into the housing, cooperating parts on the drive element and the drilling unit providing a releasable driving connection whereby the retrievable drilling unit and cutting tool may be rotated by the rotary drive element, and a fluid actuated feed element on the retrievable unit for advancing the cutting tool.

5. Drilling apparatus for use in a bore hole,

13

comprising in combination: a housing adapted to be secured to a pipe string and positioned within the bore hole, a fluid driven turbine in the housing having a rotor, the turbine being driven by pressure fluid supplied through the pipe string, a retrievable drilling unit including a rotary cutting tool adapted to be lowered through the interior of the pipe string into driving engagement with the rotor, and a fluid actuated feed element on the retrievable unit for advancing the cutting tool.

6. Apparatus for securing a core sample from the formation adjacent a bore hole, comprising in combination: a housing adapted to be secured to a pipe string and positioned within the bore hole, a prime mover in the housing having a rotary drive element, a retrievable sampling unit adapted to be lowered through the interior of the pipe string into the housing, cooperating parts on the sampling unit and drive element forming a releasable driving connection whereby the sampling unit may be driven by the rotary drive element, the sampling unit including a rotary coring tool and a feed element for advancing the coring tool into the formation.

7. Apparatus for securing a core sample from the formation adjacent a bore hole, comprising in combination: a housing adapted to be secured to a pipe string and positioned within the bore hole, a prime mover in the housing having a rotary drive element, a retrievable sampling unit adapted to be lowered through the interior of the pipe string into the housing, cooperating parts on the sampling unit and drive element forming a releasable driving connection whereby the sampling unit may be driven by the rotary drive element, the sampling unit including a rotary coring tool and a feed element for advancing and retracting the coring tool into and out of the formation.

8. Apparatus for securing a core sample from the formation adjacent a bore hole, comprising in combination: a housing adapted to be secured to a pipe string and positioned within the bore hole, a fluid-operated turbine in the housing having a rotor driven by pressure fluid supplied through the pipe string rotor, a retrievable sampling unit adapted to be lowered through the interior of the pipe string into the housing, cooperating parts on the sampling unit and rotor forming a releasable driving connection whereby the sampling unit may be driven by the turbine rotor, the sampling unit including a rotary coring tool and a fluid-operated feed element for projecting and retracting the coring tool into and out of the formation.

9. Apparatus for securing a core sample from the side wall of a bore hole, comprising in combination: a housing adapted to be secured to a pipe string and positioned within the bore hole, the housing being provided with a lateral opening in a side wall thereof, a prime mover in the housing having a rotary drive element, a retrievable sampling unit adapted to be lowered through the interior of the pipe string into the housing, cooperating parts on the sampling unit and drive element forming a releasable driving connection whereby the sampling unit may be driven by the rotary drive element, the sampling unit including a rotary coring tool adapted to extend through the said lateral opening in the housing.

10. Apparatus for securing a core sample from the side wall of a bore hole, comprising in combination: a housing adapted to be secured to a pipe string and positioned within the bore hole,

14

the housing being provided with a lateral opening in a side wall thereof, a prime mover in the housing having a rotary drive element, a retrievable sampling unit adapted to be lowered through the interior of the pipe string into the housing, cooperating parts on the sampling unit and drive element forming a releasable driving connection whereby the sampling unit may be driven by the rotary drive element, the sampling unit including a rotary coring tool and a feed element for projecting the coring tool through the said lateral opening in the housing.

11. Apparatus for securing a core sample from the side wall of a bore hole, comprising in combination: a housing adapted to be secured to a pipe string and positioned within the bore hole, the housing being provided with a lateral opening in a side wall thereof, a fluid-operated turbine in the housing having a rotor driven by pressure fluid supplied through the pipe string, a retrievable sampling unit adapted to be lowered through the interior of the pipe string into the housing, cooperating parts on the sampling unit and rotor forming a releasable driving connection whereby the sampling unit may be driven by the turbine rotor, the sampling unit including a rotary coring tool and a fluid-operated feed element for projecting and retracting the coring tool through the said lateral opening in the housing.

12. Apparatus for securing a core sample from the side wall of a bore hole, comprising in combination: a housing adapted to be secured to a pipe string and positioned within the bore hole, the housing being provided with a lateral opening in a side wall thereof, an hydraulically actuated member on the housing engageable with the side wall of the bore hole for moving the housing laterally within the bore hole to position said lateral opening against the side wall surface of the bore hole, a fluid-operated turbine in the housing having a rotor driven by pressure fluid supplied through the pipe string, a retrievable sampling unit adapted to be lowered through the interior of the pipe string into the housing, cooperating parts on the sampling unit and rotor forming a releasable driving connection whereby the sampling unit may be driven by the turbine rotor, the sampling unit including a rotary coring tool and a fluid-operated feed element for projecting and retracting the coring tool through the said lateral opening in the housing.

13. Apparatus for securing a core sample from the side wall of a bore hole, comprising in combination: a housing adapted to be secured to a pipe string and positioned within the bore hole, the housing being provided with a lateral opening in a side wall thereof, a laterally movable member on the housing engageable with the side wall of the bore hole for moving the housing laterally within the bore hole to position said lateral opening against the side wall surface of the bore hole, a prime mover in the housing having a rotary drive element, a retrievable sampling unit adapted to be lowered through the interior of the pipe string into driving engagement with said drive element, the sampling unit including a rotary coring tool and a feed element for projecting and retracting the coring tool through said lateral opening in the housing.

14. Apparatus for securing a core sample from the side wall of a bore hole, comprising in combination: a housing adapted to be secured to a pipe string and positioned within the bore hole, the housing being provided with a lateral open-

ing in a side wall thereof, a prime mover in the housing, the prime mover having an axially extending drive element provided with an axial opening, a retrievable sampling unit adapted to be lowered through the interior of the pipe string into driving engagement with said drive element, the sampling unit including a rotary coring tool at its lower end adapted to pass through said axial opening in the drive element.

15. Apparatus for securing a core sample from the side wall of a bore hole, comprising in combination: a housing adapted to be secured to a pipe string and positioned within the bore hole, the housing being provided with a lateral opening in a side wall thereof, a fluid operated turbine in the housing having a rotor driven by pressure fluid supplied through the pipe string, the rotor having an axial opening, a retrievable sampling unit adapted to be lowered through the interior of the pipe string into the housing, cooperating parts on the sampling unit and rotor forming a releasable driving connection whereby the sampling unit may be driven by the turbine rotor, the sampling unit including a coring tool at its lower end adapted to pass through said axial opening in the drive element.

16. Apparatus for securing a core sample from the side wall of a bore hole, comprising in combination: a housing adapted to be secured to a pipe string and positioned within the bore hole, the housing being provided with a lateral opening in a side wall thereof, a fluid operated turbine in the housing having a rotor driven by pressure fluid supplied through the pipe string, the rotor having an axial opening, a seat formed in the opening, a retrievable sampling unit adapted to be lowered through the interior of the pipe string to rest on said seat, cooperating parts on the sampling unit and rotor forming a releasable driving connection whereby the sampling unit may be driven by the turbine rotor, the sampling unit including a coring tool at its lower end adapted to pass through said axial opening in the drive element, the upper end of the retrievable sampling unit extending above the turbine rotor.

17. Drilling apparatus for use in a bore hole, comprising in combination: a housing adapted to be secured to a pipe string and positioned within the bore hole, a prime mover in the housing having a rotor drive element, said element being provided with an axial opening, a retrievable drilling unit adapted to be lowered through the interior of the pipe string into driving relationship with said drive element, said retrievable drilling unit including a rotary cutting tool adapted to pass through said axial opening in the rotary drive element.

18. Drilling apparatus for use in a bore hole, comprising in combination: a housing adapted to be secured to a pipe string and positioned within the bore hole, the housing being provided with a lateral opening in a side wall thereof, a prime mover in the housing having a rotary drive element, a retrievable drilling unit adapted to be lowered through the interior of the pipe string into the housing, cooperating parts on the drilling unit and drive element forming a releasable driving connection whereby the drilling unit may be driven by the rotary drive element, the drilling unit including a rotary cutting tool adapted to extend through the said lateral opening in the housing.

19. Drilling apparatus for use in a bore hole, comprising in combination: a housing adapted to

be secured to a pipe string and positioned within the bore hole, the housing being provided with a lateral opening in a side wall thereof, a fluid operated turbine in the housing having a rotor driven by pressure fluid supplied through the pipe string, a retrievable drilling unit adapted to be lowered through the interior of the pipe string into the housing, cooperating parts on the drilling unit and rotor forming a releasable driving connection whereby the drilling unit may be driven by the turbine rotor, the drilling unit including a rotary cutting tool and a fluid operated feed element for projecting and retracting the cutting tool through the said lateral opening in the housing.

20. Drilling apparatus for use in a bore hole, comprising in combination: a housing adapted to be secured to a pipe string and positioned within the bore hole, a prime mover in the housing driven by pressure fluid supplied through said pipe string, said prime mover having a rotary drive element, a retrievable drilling unit including a rotary cutting tool adapted to be lowered through the interior of the pipe string into the housing, cooperating parts on the drive element and the drilling unit providing a releasable driving connection whereby the retrievable drilling unit and cutting tool may be rotated by the rotary drive element, a fluid actuated feed element on the retrievable unit for advancing and retracting the cutting tool, a signal valve movable from an inoperative position providing a relatively unrestricted passage from the drill string into the housing to an operative position restricting said passage, the signal valve in operative position imposing a back pressure on the fluid in the pipe string to provide a signal at its upper end, and mechanical linkage operable upon completion of retracting movement of the cutting tool to move the valve to operative position.

21. Apparatus for securing a core sample from the side wall of a bore hole, comprising in combination: a housing adapted to be secured to a pipe string and positioned within the bore hole, the housing being provided with a lateral opening in a side wall thereof, a fluid-operated turbine in the housing having a rotor driven by pressure fluid supplied through the pipe string, a retrievable sampling unit adapted to be lowered through the interior of the pipe string into the housing, cooperating parts on the sampling unit and rotor forming a releasable driving connection whereby the sampling unit may be driven by the turbine rotor, the sampling unit including a rotary coring tool and a fluid-operated feed element for projecting and retracting the coring tool through the said lateral opening in the housing, a signal valve movable from an inoperative position providing a relatively unrestricted passage from the drill string into the housing to an operative position restricting said passage, the signal valve in operative position imposing a back pressure on the fluid in the pipe string to provide a signal at its upper end, and mechanical linkage operable upon completion of retracting movement of the coring tool to move the valve to operative position.

22. Apparatus for securing a core sample from the side wall of a bore hole, comprising in combination: a housing adapted to be secured to a pipe string and positioned within the bore hole, the housing being provided with a lateral opening in a side wall thereof, a retrievable sampling unit adapted to be lowered through the interior

17

of the pipe string into the housing, the sampling unit including a coring tool adapted to extend through said lateral opening in the housing, a feed element operable to advance and retract the coring tool through said lateral opening, a signal valve movable from an inoperative position providing a relatively unrestricted passage from the drill string into the housing to an operative position restricting said passage, the signal valve in operative position imposing a back pressure on the fluid in the pipe string to provide a signal at its upper end, and mechanical linkage operable upon completion of retracting movement of the coring tool to move the valve to operative position.

23. Apparatus for securing a core sample from the side wall of a bore hole, comprising in combination: a housing adapted to be secured to a pipe string and positioned within the bore hole, the housing being provided with a lateral opening in a side wall thereof, a retrievable sampling unit adapted to be lowered through the interior of the pipe string into the housing, the sampling unit including a coring tool adapted to extend through said lateral opening in the housing, a feed element operable by pressure fluid supplied through the pipe string to advance and retract the coring tool through said lateral opening, a valve movable from an inoperative position providing a relatively unrestricted passage from the drill string into the housing to an operative position restricting said passage, and mechanical linkage including a member movable by said feed element, said member including inter-engaging parts adapted to render the member effective to actuate the valve when the coring tool approaches its retracted position.

24. Apparatus for securing a core sample from the side wall of a bore hole, comprising in combination: a housing adapted to be secured to a pipe string and positioned within the bore hole, the housing being provided with a lateral opening in a side wall thereof, a retrievable sampling unit adapted to be lowered through the interior of the pipe string into the housing, the sampling unit including a coring tool adapted to extend through said lateral opening in the housing, a feed piston movable within a cylinder provided on the sampling unit by pressure fluid supplied through the drill string and operably connected to advance the coring tool through said lateral opening in the housing, a valve movable from an inoperative position providing a relatively unrestricted passage from the drill string into the housing to an operative position restricting said passage, a latch device for maintaining the valve in its inoperative position, a member extending axially of the sampling unit and adapted to be moved axially by said feed piston, cooperating parts on said member adapted to render the member effective to trip the latch device to actuate the valve when the coring tool approaches its retracted position.

25. Apparatus for securing a core sample from the side wall of a bore hole, comprising in combination: a housing adapted to be secured to a pipe string and positioned within the bore hole, the housing being provided with a lateral opening in a side wall thereof, a retrievable sampling unit adapted to be lowered through the interior of the pipe string into the housing, the sampling unit including a coring tool adapted to extend through said lateral opening in the housing, a feed piston positioned within a cylinder provided on the sampling unit, said piston being movable in response to pressure fluid supplied through

18

said pipe string and operably connected to advance and retract the coring tool through said lateral opening in the housing, a valve movable from an inoperative position providing a relatively unrestricted passage for the pressure fluid from the drill string into the housing to an operative position restricting the flow of pressure fluid through said passage, a latch device for maintaining the valve in its inoperative position, a trip member extending axially of the sampling unit and adapted to be moved axially by said feed piston, cooperating parts on said member adapted to increase the effective length thereof upon completion of movement of the feed piston in a direction to advance the coring tool, and cooperating parts whereby said elongated trip member may release the latch device as the feed piston approaches its retracted position.

26. Apparatus for securing a core sample from the side wall of a bore hole, comprising in combination: a housing adapted to be secured to a pipe string and positioned within the bore hole, the housing being provided with a lateral opening in a side wall thereof, a retrievable sampling unit adapted to be lowered through the interior of the pipe string into the housing, the sampling unit including a coring tool adapted to extend through said lateral opening in the housing, a feed piston positioned within a cylinder provided on the sampling unit, said piston being movable in response to pressure fluid supplied through said pipe string and operably connected to advance and retract the coring tool through said lateral opening in the housing, a valve movable from an inoperative position providing a relatively unrestricted passage for the pressure fluid from the drill string into the housing to an operative position restricting the flow of pressure fluid through said passage, a latch device for maintaining the valve in its inoperative position, a sectional trip member adapted to release the latch device whereby the valve may move to operative position to restrict the flow of pressure fluid, a first stop on a lower section of said member engageable by said feed piston near one end of its travel, cooperating parts connecting the lower section with an upper section of said member and adapted to increase the effective length of the sectional member upon movement of the stop by the feed piston, and a second stop on the lower section engageable by the feed piston near the other end of its travel to move the elongated sectional member in a direction to release the latch device.

27. Drilling apparatus for use in a bore hole, comprising in combination: a housing adapted to be secured to a pipe string and positioned within the bore hole, a drilling unit including a cutting tool positioned within the housing, a feed element on the drilling unit for advancing the cutting tool from the interior to the exterior of the housing, said feed element being subjected on one side to pressure fluid supplied through the pipe string and on the other side to pressure within the bore hole, the housing including a member provided with an orifice through which pressure fluid from the interior of the pipe string escapes into the bore hole whereby a pressure differential is maintained between the interior and exterior of the pipe string.

28. Apparatus for securing a core sample from the formation adjacent a bore hole, comprising in combination: a housing adapted to be secured to a pipe string and positioned within the bore hole, a fluid operated turbine in the housing having a

19

rotor driven by pressure fluid supplied through the pipe string, a retrievable sampling unit adapted to be lowered through the interior of the pipe string into driving relationship with the turbine rotor, the sampling unit including a rotary coring tool, a feed element on the sampling unit for advancing the coring tool outwardly from the interior of the housing, said feed element being subjected on one side to pressure fluid supplied through the pipe string and on the other side to pressure within the bore hole, the housing including a member provided with an orifice through which pressure fluid from the interior of the pipe string escapes into the bore hole whereby a pressure differential is maintained between the interior and exterior of the pipe string.

29. Apparatus for securing a core sample from the side wall of a bore hole, comprising in combination: a housing adapted to be secured to a pipe string and positioned within the bore hole, the housing being provided with a lateral opening in a side wall thereof, a fluid-operated turbine in the housing having a rotor driven by pressure fluid supplied through the pipe string, a retrievable sampling unit adapted to be lowered through the interior of the pipe string into the housing, cooperating parts on the sampling unit and rotor forming a releasable driving connection whereby the sampling unit may be driven by the turbine rotor, the sampling unit including a rotary coring tool, a feed element on the drilling unit for advancing the rotary coring tool through the said lateral opening in the housing, said feed element being subjected on one side to pressure fluid supplied through the pipe string and on the other side to pressure within the bore hole, the housing including a member positioned below the turbine and provided with an orifice through which pressure fluid may escape from the interior of the pipe string into the bore hole.

30. Drilling apparatus for use in a bore hole, comprising in combination: a housing adapted to be secured to a pipe string and positioned within the bore hole, a drilling unit including a cutting tool positioned within the housing, a feed element on the drilling unit for advancing the cutting tool from the interior of the housing into the formation adjacent the bore hole, said feed element being subjected on one side to pressure fluid supplied through the pipe string and on the other side to pressure within the bore hole, the housing including a member provided with an orifice through which pressure fluid from the interior of the pipe string escapes into the bore hole, a movable valve element positioned to restrict flow through the orifice, and a spring acting to move the valve in a flow-restricting direction.

31. Apparatus for securing a core sample from the side wall of a bore hole, comprising in combination: a housing adapted to be secured to a pipe string and positioned within the bore hole, the housing being provided with a lateral opening in a side wall thereof, a fluid-operated turbine in the housing having a rotor driven by pressure fluid supplied through the pipe string, a retrievable sampling unit adapted to be lowered through the interior of the pipe string into the housing, cooperating parts on the sampling unit and rotor forming a releasable driving connection whereby the sampling unit may be driven by the turbine rotor, the sampling unit including a rotary coring tool and a fluid-operated feed element for projecting and retracting the

20

coring tool through the said lateral opening in the housing, the housing including a member provided with an orifice through which pressure fluid from the interior of the pipe string may escape into the bore hole, a movable valve element positioned to restrict flow through the orifice, and a spring acting to move the valve in a flow-restricting direction.

32. Apparatus for securing a core sample from the formation adjacent a bore hole, comprising in combination: a housing adapted to be secured to a pipe string and positioned within the bore hole, a prime mover in the housing having a rotary drive element, a retrievable sampling unit adapted to be lowered through the interior of the pipe string into the housing, cooperating parts on the sampling unit and drive element forming a releasable driving connection whereby the sampling unit may be driven by the rotary drive element, the sampling unit including a rotary coring tool and a feed element for advancing and retracting the coring tool into and out of the formation, a barrier near the lower end of the retrievable sampling unit adapted to exclude bore hole detritus from the interior of the unit while it is being lowered through the pipe string, the barrier having a port extending therethrough, and a valve member normally closing the port and movable to an inoperative position by fluid pressure within said unit.

33. Drilling apparatus for use in a bore hole, comprising in combination: a housing adapted to be secured to a pipe string and positioned within the bore hole, a drilling unit in the housing including a rotary cutting tool, a feed piston positioned within a cylinder provided on the drilling unit, a movable barrier member on the drilling unit subjected on its upper side to pressure of a first fluid supplied through said pipe string, the drilling unit being provided with a passage for a second fluid, the passage connecting the lower side of the barrier member to the cylinder, whereby the feed piston moves in response to motion of the barrier member to move the cutting tool out of the housing.

34. Drilling apparatus for use in a bore hole, comprising in combination: a housing adapted to be secured to a pipe string and positioned within the bore hole, a drilling unit in the housing including a rotary cutting tool, a feed piston positioned within a cylinder provided on the drilling unit, a movable barrier member on the drilling unit subjected on its upper side to pressure of a first fluid supplied through said pipe string, the drilling unit being provided with a passage for a second fluid, the passage connecting the lower side of the barrier member to the cylinder, whereby the feed piston moves in response to motion of the barrier member to move the cutting tool out of the housing, and a valve device operatively interposed in said passage and adapted to deliver the second fluid into the cylinder either above or below the feed piston.

35. Apparatus for securing a core sample from the side wall of a bore hole, comprising in combination: a housing adapted to be secured to a pipe string and positioned within the bore hole, the housing being provided with a lateral opening in a side wall thereof, a retrievable sampling unit adapted to be lowered through the interior of the pipe string into the housing, the sampling unit including a coring tool adapted to extend through said lateral opening in the housing, a feed piston positioned with a cylinder provided on the sampling unit, and operably connected to ad-

vance and retract the coring tool through said lateral opening in the housing, a movable barrier member on the sampling unit subjected on its upper side to pressure fluid supplied through said pipe string, the sampling unit being provided with an oil filled passage connecting the lower side of the barrier member to the cylinder, whereby the feed piston moves in response to motion of the barrier member to move the coring tool through said lateral opening in the housing.

36. Apparatus for securing a core sample from the side wall of a bore hole, comprising in combination: a housing adapted to be secured to a pipe string and positioned within the bore hole, the housing being provided with a lateral opening in a side wall thereof, a retrievable sampling unit adapted to be lowered through the interior of the pipe string into the housing, the sampling unit including a coring tool adapted to extend through said lateral opening in the housing, a feed piston positioned with a cylinder provided on the sampling unit, and operably connected to advance and retract the coring tool through said lateral opening in the housing, a movable barrier member on the sampling unit subjected on its upper side to pressure fluid supplied through

20
25

said pipe string, the sampling unit being provided with an oil filled passage connecting the lower side of the barrier member to the cylinder, whereby the feed piston moves in response to motion of the barrier member to move the coring tool through said lateral opening in the housing, and a valve device operatively interposed in said passage and adapted to deliver oil into the cylinder either above or below the feed piston.

PAUL DEAN CORNELIUS.
